UNITED STATES PATENT OFFICE.

ROBERT J. JOHNSON, OF SPOKANE, WASHINGTON.

SHIRT RETAINER.

Application filed March 31, 1925. Serial No. 19,631.

The present invention relates to improvements in retaining devices for use upon wearing apparel, and the primary object of the invention is to provide a device of this character which is especially well adapted for use in preventing the lower portions of a shirt from working upward out of the trousers of the wearer.

A further object of the invention is to provide an improved retainer for shirts, which is intended for detachable connection with the tail and front blanks of the shirt for effectively holding the lower portions of the shirt below the waist line in a manner so as to not afford any discomfort to the wearer of the device.

A still further object of the invention is to provide a device of this character which is extremely simple in construction, and which may be readily adjusted longitudinally to meet the requirements of the person wearing the device.

A still further object of the invention being to provide a retainer of the character described embodying sanitary features of construction, and being so formed as to become self adjusting when placed in position upon the wearer.

Other objects and advantages of the invention will be apparent during the course of the following detailed description, taken in connection with the accompanying drawings, forming a part of this specification, and in which drawing,

Figure 1 is a view showing the improved retainer in position upon a wearer for preventing the shirt from being pulled upwardly.

Figure 2 is a plan view of the outer side of the preferred form of the invention, the same being shown in a flat condition.

Figure 3 is a plan view of the outer side of a slightly modified form of the invention from that shown in Figures 1 and 2.

Figure 4 is a longitudinal section on the line 4-4 of Figure 2; and

Figure 5 is a fragmentary sectional view showing the connection between the elastic and inelastic portions of the retainer as illustrated in Figure 2.

Referring to the drawing in detail, and wherein similar reference characters designate corresponding parts throughout the several views, the letter A may designate the showing of the preferred form of the invention, and B the modified form thereof.

In the modified form of the invention as

In the example shown, the shirt C may be of the coat type, embodying a tail portion 6 and front blanks 7 divided centrally of the front of the shirt as is customary in the construction of coat shirts.

Referring first to the form A of the invention, and which is of Y-shape in plan, the same embodies two strips of elastic webbing 9 arranged in V-shaped converging relation to one another, and joined at the apex of the sections to one end of an inelastic tang portion 10. This inelastic portion 10, which may be of leather or other suitable flexible material, is formed of independent inner and outer sections 11 and 12 respectively arranged in aligning relation one upon the other, and formed at their inner ends with enlarged head portions 13 between which the inner ends of the elastic webbings 9 are disposed and secured as by stitching 14 extending through the webbing and head portions 13. The clasp 15, preferably includes a terminally disposed stud portion 16 having an elongated metal clamping loop 17 associated therewith for cooperating in receiving a portion of the shirt material in a well known manner. A flexible non-elastic strip 18 is looped through the stud portion 16 and extends inwardly upon itself, and has its inner ends secured between the outer end portions of the sections 11 and 12 as by stitching 19. A transverse stitching 20 provided in the folds of the strip 18 at a point adjacent the terminals of the sections 11 and 12, forms a loop opening 21 for reception of one end of the clamping loop 17.

The elastic strips 9 which are extensible for adjustment of the retainer to meet the requirements of the wearer, are each provided with the usual tri-bar buckles 22, and to the central transverse bar of which one end of each strip 9 is attached as by stitching or the like. This adjusting buckle arrangement forms a double or loop portion 23 at the free ends of the strips 9 for slidably receiving a cross bar 24 of the clasps 25. These clasps 25 preferably include stud portions 26, elongated loop portions 27, and the non-elastic strip 28; said loop portions 27 preferably being provided with two cross bars at their inner ends, the terminal cross bars 24 forming an anchor for the looped ends of the strips 9, and the cross bar 29 forming attaching means for one end of the non-elastic clasp strip 28.

illustrated in Figure 3, and wherein the principle of the longitudinally adjustable elastic portions and the non-extensible portion is carried out in a slightly different manner; in this showing, the adjustable elastic portion is of a single strip in contradistinction to a substantially bifurcated elastic portion as illustrated in Figure 2. In the showing in Figure 3, 9' may designate the longitudinally adjustable elastic portion having the clasp 25' attached to the looped end 23' thereof, and having its opposite end secured between the inner ends of a non-extensible portion 10' provided with the clasp 15'.

Thus it will be seen that in both forms of the retainer is embodied the principle of a fastener adapted to engage the garment, which is non-adjustably carried by a piece 20 of cloth, leather, or other non-extensible material, and to which latter is connected one or more pieces of elastic material, which support in an adjustable manner, the other clasp or fastener for engaging the garment.

25. In use, the clasp 15 may first be attached to the bottom portion of the back of the shirt, and the bifurcated or extensible elastic portions 9 brought between the legs and the clasps 25 attached to the respective 30 fronts 7 of the shirt. In use of the form as shown in Figure 3, it will become necessary to place both fronts 7 of the shirt in the

clasp 15', should the shirt upon which the retainer is being used be of the coat type as is illustrated in the drawing.

35

From the foregoing description of this invention it will be apparent that an extremely efficient device of this character has been provided which embodies hygienic principles, and which may be worn without 40 discomfort when applied for the purpose for which it is intended.

Changes in detail may be made to the forms of the invention herein shown and described, without departing from the spirit 45 of the invention or the scope of the following claim.

I claim:

A shirt retaining device comprising a tang portion embodying superposed inelastic 50 portions each formed with an elongated strip section having an enlargement at one end thereof and forming a divided head portion, elastic strips secured in angular relation at one end between the divided head 55 portion and extending therefrom in diverging relation, clasps adjustably carried by the free end portion of each elastic strip, and a clasp embodying a flexible strip secured between the elongated strip sections at 60 the opposite end of the strips from that at which the enlargements are formed.

ROBERT J. JOHNSON.
